United States Patent Office

Des. 188,501
Patented Aug. 2, 1960

188,501

GRILL

John T. Wood, 312 Wyndhurst Ave., Baltimore, Md.

Filed Mar. 5, 1959, Ser. No. 54,852

Term of patent 14 years

(Cl. D44—1)

FIG. 3

Figure 1 is a perspective view;

Figure 2 is a cross-sectional view taken upon section line 2—2 of Figure 1 with the handle removed; and

Figure 3 is a bottom perspective view with the handle removed.

I claim:

The ornamental design for a grill, as shown.

References Cited in the file of this patent

UNITED STATES PATENTS

D. 26,238	Brooks et al. -----	July 24, 1860
676,479	Wagner -----	June 18, 1901
1,885,325	Bagley -----	Nov. 1, 1932

FOREIGN PATENTS

3,416	Great Britain -----	A.D. 1885